(57) **CLAIM**

The ornamental design for a traveler mug, as shown and described.

DESCRIPTION

FIG. 1 is a top right perspective view of a traveler mug showing my new design.

FIG. 2 is a front elevational view of the design.

FIG. 3 is a rear elevational view of the design.

FIG. 4 is a right side elevational view of the design.

FIG. 5 is a left side elevational view of the design.

FIG. 6 is a top plan view of the design.

FIG. 7 is a bottom plan view of the design.

FIG. 8 is a top right perspective view of a second embodiment of the design without a handle.

FIG. 9 is a front elevational view of the second embodiment of the design.

FIG. 10 is a rear elevational view of the second embodiment of the design.

FIG. 11 is a right side elevational view of the second embodiment of the design.

FIG. 12 is a left side elevational view of the second embodiment of the design.

FIG. 13 is a top plan view of the second embodiment of the design; and,

FIG. 14 is a bottom plan view of the second embodiment of the design.
